(57) **CLAIM**

The ornamental design for a computer input device, as shown and described.

DESCRIPTION

FIG. 1 is a perspective view of a computer input device in an open configuration showing the new design.

FIG. 2 is a right side elevational view thereof.

FIG. 3 is a left side elevational view thereof.

FIG. 4 is a front view thereof.

FIG. 5 is a rear view thereof.

FIG. 6 is a top plan view thereof.

FIG. 7 is a bottom plan view thereof.

FIG. 8 is a bottom perspective view of the computer input device in a closed configuration.

FIG. 9 is a right side perspective view thereof.

FIG. 10 is a rear perspective view of the computer input device in an open configuration.

FIG. 11 is a bottom perspective view thereof; and,

FIG. 12 is a second bottom perspective view thereof.

The broken line regions and the unshaded areas there within, e.g., illustrative of the scroll wheel, textured sides, feet, side button, arrow on retractable base, optics, battery compartment, and bottom label region, are for illustrative purposes only and form no part of the claimed design.
